DETACHABLE COMBINATION GARMENT

Philip H. Robbins, New York, N. Y., assignor to
Poirette Corsets, Inc., New York, N. Y.

Application October 20, 1936, Serial No. 106,647

10 Claims. (Cl. 2—30)

This invention relates to a detachable combination garment for women's wear, more particularly, an undergarment of the combined detachable brassière and girdle or corset type.

5 The invention aims to provide, in a manner as hereinafter set forth, a garment of the class referred to, whereby when worn, the wearer has freedom of the front and back of the brassière and gives the wearer the full freedom of action 10 of a separate brassière relative to the girdle or corset and at the same time always bringing the lower and upper part of the front and back of the brassière into their original positions when standing, or in other words, eliminating the brassière 15 from hiking up on the girdle or corset at the front and back of the latter.

A further object of the invention is to provide, in a manner as hereinafter set forth, a garment including an upper element in the form of a 20 brassière, a lower element in the form of a girdle or corset and with the lower portion of the upper element overlapping and encompassing throughout the upper portion of the lower element. The 25 said elements having coacting means, so disposed at the fronts and backs thereof, for detachably connecting them together and for imparting to the brassière all the relief and freedom of a 30 separate brassière, as well as to permit of the upper element being laundered without any interference with or from the lower element.

A further object of the invention is to provide, in a manner as hereinafter set forth, a combination garment including an upper element in the 35 form of a brassière and a lower element in the form of a girdle or corset and with said elements having coacting parts for detachably connecting them together to permit of a worn or damaged element being removed and a new one substituted without discarding the non-worn or non-damaged element.

A further object of the invention is to provide, 40 in a manner as hereinafter set forth an undergarment formed of an upper element, in the form of a brassière, a lower element in the form of a girdle or corset having its upper portion overlapped by the lower portion of the brassière and spaced coacting means positioned respectively at the bottom of the front of the brassière, at the bottom of the back of the brassière, at the 45 front of the girdle intermediate its top and bottom, at the back of the girdle intermediate its top and bottom, in forward relation with respect to what may be termed the axillary lines of the 50 girdle and in rearward relation with respect to 55

the said axillary lines for elastically and detachably connecting said upper element to said lower element thereby imparting to the brassière all the relief and freedom of a separate or non-connected brassière.

Further objects of the invention are to provide, in a manner as hereinafter set forth, a combination garment which is simple in its construction, strong, durable, formed of an upper and a lower element disposed in overlapping relation 10 elastically and detachably connected together, overcoming discomfort from a binding standpoint when worn, thoroughly efficient for the purpose intended thereby, readily assembled and comparatively inexpensive to manufacture.

A further object of the invention is to provide, in a manner as hereinafter set forth, a brassière or upper confining garment which may be attached to a girdle, corset or other lower garment 20 and which will have relatively free movement throughout with respect to such lower garment while at the same time it is maintained in the initial desired relation to said lower garment.

A further object of the invention is to provide, 25 in a manner as hereinafter set forth, a corset, girdle or other lower garment of such type having means for connecting an upper garment to the front and rear of the hip lines of the lower garment for permanently maintaining the upper garment in yieldable connected relation with respect to the lower garment.

With the foregoing and other objects which may hereinafter appear, the invention consists 35 of the novel construction, combination and arrangement of parts as will be more specifically described and are as illustrated in the accompanying drawings wherein is shown embodiments of the invention, but it is to be understood that changes, variations and modifications 40 may be resorted to which fall within the scope of the invention as claimed.

In the drawings:—

Figure 1 is a perspective view looking towards 45 the front of the garment and with the latter positioned upon the simulation of a wearer.

Figure 2 is a view similar to Figure 1 looking towards the back of the garment,

Figure 3 is a disassembled view in elevation of 50 the upper and lower elements of the garment, looking towards the front of the latter,

Figure 4 is a view similar to Figure 3 looking 55 towards the back of the garment,

Figure 5 is a fragmentary view in elevation 55

upon an enlarged scale illustrating the form of anchoring devices employed.

Figure 6 is a fragmentary view in front elevation upon an enlarged scale looking towards the front of the garment.

Figure 7 is a view similar to Figure 6 of a modified form, and

Figure 8 is a view similar to Figure 6 illustrating still another modified form.

10 The garment is of the combined type and includes an upper element 1 in the form of a brassière and a lower element 2 in the form of a girdle or corset. The lower portion of the brassière 1 overlaps and completely encompasses the 15 upper portion of the lower element 2. The latter will be hereinafter termed a girdle and it is to be understood that the term girdle will apply to a corset.

With reference to Figures 1 to 6 the brassière 1 20 has connected thereto and depending from the bottom edge of its front a resilient loop forming means consisting of a resilient continuous front strap 3 formed of an intermediate part 4 and a pair of end parts 5, 6. At the points where the 25 intermediate part 4 merges into the end parts 5, 6, the strap 3 is connected to the lower edge of the front of the brassière, at points spaced from each side of the vertical median of said front by 30 securers 7, 8 in the form of stitching. Between the securers 7, 8 and interposed between the central portion of the bottom edge of the front of the brassière and the intermediate part 4, a stitching 9 is employed for connecting said intermediate part, between the securers 7, 8 with 35 the front of the brassière in spaced relation to the central portion of the said bottom edge. The end parts 5, 6 are folded upon themselves in a manner to provide a pair of inwardly inclined oppositely disposed folds 10, 11 having 40 their upper termini anchored to the bottom edge of the front of the brassière outwardly adjacent the securers 7, 8. The manner of setting up the end parts 5, 6 form oppositely and horizontally extending elastic front loops 12, 13 of substantially 45 triangular contour and horizontally. The non-folded portions of the end parts 5, 6 and the intermediate part 4 provide the strap 3, when it is in normal position with an arcuate stretch and in this connection attention is directed to Figure 3.

The brassière has connected thereto and depending from the bottom edge of the back thereof of a resilient loop forming means consisting of a resilient continuous rear strap 14 formed of an 55 intermediate part 15 and a pair of end parts 16, 17. At the points where the intermediate part 15 merges into the end parts 16, 17, the strap 14 is connected to the lower end of the back of the brassière at points spaced from each side of the 60 vertical median of said back by securers 18, 19 in the form of stitching. Between the securers 18, 19 and interposed between the central portion of the bottom edge of the back of the brassière and the intermediate part 15 a stitching is employed for connecting said intermediate part, between the securers 18, 19 to the back of the brassière in spaced relation to the central portion of the said bottom edge. The ends 16, 17 are folded upon themselves in a manner to provide a 65 pair of inwardly inclined oppositely disposed folds 21, 22 having their upper termini anchored to the bottom edge of the back of the brassière outwardly adjacent to the securers 18, 19. The manner of setting up the end parts 16, 17 form 70 oppositely and horizontally extending elastic rear 75 loops 23, 24 substantially of triangular contour.

The non-folded portions of the end parts 16, 17 and the intermediate part 15 provide the strap 14, when it is in normal position, with an arcuate stretch. The strap 14 is arranged in the same 5 manner as the strap 3, but strap 14 is of greater length than strap 3. The intermediate part 15 of strap 14 substantially corresponds in length to the intermediate part 4 of the strap 3. The end parts 16, 17 of the strap 14 are of greater length 10 than the end parts 5, 6 of the strap 3 whereby the loops 22, 23 are larger than the loops 12, 13. The loop 12, 13, 22, 23 constitute connecting or anchoring devices.

The front of the girdle, between its top and 15 bottom, is provided with a pair of oppositely and horizontally extending spaced aligned upstanding anchoring devices 25, 26 of like form. Each anchoring device has one end secured to the front of the girdle. The anchoring devices extend 20 towards each other and are arranged in forward relation with what may be termed the axillary lines of the girdle. Each anchoring device consists of a length of tape 27 folded upon itself in a manner to provide a horizontal upper fold 28 25 and a downwardly outwardly inclined lower fold 29. The bend 30 between the folds 28, 29 inclines outwardly from its lower to its upper end. The folds 28, 29 adjacent to and in proximity to the bend 30 are anchored together by a row of stitching 31 which provides a barrel 32 inclining outwardly from its lower to its upper end to the vertical. The fold 28 overlaps the upper portion of the fold 29. The folds 28 and 29 are secured adjacent their free end edges to the girdle 2 by 35 the rows of stitching 33. Each anchoring device includes an upstanding coupler 34 which is disposed at an outward inclination from its bottom to its top to the vertical. The coupler is formed lengthwise thereof with an inclined slot 35 to 40 provide an inclined pivot 36 which extends through the barrel 32. The coupler 34 is of greater length than the length of the barrel 32. The upstanding coupler 34 is cut out to form an inclined passage 37 lengthwise thereof which is closed at its upper end and open at the bottom edge of the coupler. The side wall 38 of a passage 37 has its lower portion, as at 39, inclined away from the side wall 40 of passage 37. The lower end of the side wall 40 of passage 37 is 45 shouldered as at 41. The coupler 34 is permanently connected to the tape 27. The slots 35, 37 are disposed at the same inclination as that of the coupler.

The anchoring devices 25, 26 coact with the 55 loops 12, 13 for elastically, slidably and detachably connecting the bottom edge of the front of the brassière to the front of the hip lines at the front of the girdle.

The front and back of the brassière are indicated at 42, 43 respectively. The front and back of the girdle are indicated at 44, 45 respectively. The simulation of the wearer on which is positioned the combination garment is indicated at 46.

The back 45 of the girdle 2 rearwardly of the axillary lines of the latter has connected thereto a pair of oppositely disposed spaced aligning upstanding rear anchoring devices 47, 48 and each of which is of the same form as an anchoring device 25 or 26 and each has one end connected to the girdle intermediate the top and bottom of the latter. The devices 47, 48 extend towards each other and are arranged in rearward relation with respect to the axillary lines of the girdle. 75

The couplers forming parts of the anchoring devices 47, 48 are indicated at 49, 50. The couplers 49, 50 coact with the loops 23, 24 for elastically, slidably and detachably connecting the back of the brassière 1 to the back of the girdle 2. The anchoring devices 47, 48 are arranged below the anchoring device 25, 26.

When the anchoring devices 25, 26 are connected with the loops 12, 13, the strap 3 will appear as shown in Figure 1. When the anchoring devices 47, 48 coact with the loops 23, 24, the strap 14 will appear as shown in Figure 2.

With reference to Figure 7 the construction of the combination garment will be the same as that shown in Figures 1 to 6 with this exception that the upper part of the straps overlap, for a portion of their length, the bottom of the front and back of the brassière for a portion of its length and the straps are connected to the brassière by cross stitching. Figure 7 illustrates but one strap and is indicated at 51 and the cross stitching which secures the strap to the brassière is indicated at 52. Otherwise than that as stated, the modification shown in Figure 7 will be the same as that shown in Figures 1 to 6.

In the form shown in Figure 8, the girdle will be of the same construction as that shown in Figures 1 to 6. The difference between the form shown in Figure 8 and the other constructions resides in the manner of setting up the elastic loop forming means. Figure 8 illustrates only the front of the brassière and the girdle. The back of the brassière will be constructed in the same manner as the front thereof. The brassière in Figure 8 is indicated at 53 and its front at 54. The girdle in Figure 8 is designated 55 and its front at 56. The loop forming means which is associated with the back 54 consists of a pair of oppositely extending elastic straps 57, 58.

The strap 57 is bent upon itself to form a pair of folds 58, 59. The fold 59 extends inwardly and at an upward inclination with respect to the fold 58. The free ends of the folds 58, 59 are spaced from each other and are secured at spaced points of the bottom edge of the front 54 as at 60, 61. The manner of setting up the strap 57 provides a loop 62 of substantially triangular form.

The strap 58 is bent upon itself to form a pair of folds 63, 64. The fold 64 extends inwardly and at an upward inclination with respect to the fold 63. The free ends of the folds 63, 64 are spaced from each other and are secured at spaced points of the bottom edge of the front 54 as at 65, 66. The manner of setting up the strap 58 provides a loop 67 of substantially triangular form. The front 56 of the girdle 55 has a pair of anchoring devices 68, 69 of the same form and arrangement as the anchoring devices 25, 26. The couplers 70 of the anchoring devices 68, 69 coact with the loops 62, 67 for elastically, slidably and detachably connecting the front 54 of the brassière 53 to the front 56 of the girdle 55. The back of the brassière 53, not shown, will be constructed in the same manner as the front of the brassière. The back of the girdle will be constructed in the same manner as the front of the girdle. Otherwise than that as stated, the modified form shown in Figure 8 will be the same as the form shown in Figures 1 to 6.

The brassière of any of the forms shown will be provided with shoulder straps and these straps are indicated at 71, 72 in connection with the brassière 1. The girdle 2 will be provided with straps at its bottom for supporting stockings and these straps are indicated at 73, 74 with respect to the girdle 2.

The elastic loop forming means or the parts of the garment which provide the elastic loop forming means extend downwardly at opposite inclinations with respect to the brassière. The inclination of the loop forming means at the front of the brassière is less than the inclination of the loop forming means at the back of the brassière.

When the two elements of the garment are connected together and mounted on the wearer, with reference to the forms shown in Figures 1 to 7, the straps 3, 14 and 51 singly bear against the outer face of the girdle, but at the same time the arrangement is such that the brassière has the desired freedom to prevent possibility of discomfort or from hiking up relative to the girdle.

It is to be understood that the stitching wherever mentioned can be of any suitable character for permitting the attainment of the objects of this invention and that particularly the stitching shown for securing the intermediate portions of the elastic straps to the back and front of the brassière may be binding or plain sewing. It is also to be understood that in the modified form shown in Figure 8, the anchoring devices 68, 69 may be resilient and the means forming the loops 62, 64 may be of non-elastic material.

What I claim is:—

1. A combination garment comprising an upper and a lower element for encompassing the body of the wearer, the upper portion of the lower element being encompassed by the lower portion of the upper element, spaced aligned front anchoring devices forwardly of the axillary lines of the lower element, spaced aligned rear anchoring devices rearwardly of the axillary lines of the lower element, elastic loop forming means at the bottom of the front of the upper element slidably and detachably engaging in said front anchoring devices for elastically coupling the front of the upper element to the front of the lower element, and elastic loop forming means at the bottom of the back of the upper element slidably and detachably engaging with said rear anchoring devices for elastically coupling the back of the upper element to the back of the lower element.

2. A combination garment comprising an upper and a lower element for encompassing the body of the wearer, the upper portion of the lower element being encompassed by the lower portion of the upper element, spaced aligned front anchoring devices forwardly of the axillary lines of the lower element, spaced aligned rear anchoring devices rearwardly of the axillary lines of the lower element, elastic loop forming means at the bottom of the front of the upper element slidably and detachably engaging in said front anchoring devices for elastically coupling the front of the upper element to the front of the lower element, elastic loop forming means at the bottom of the back of the upper element slidably and detachably engaging with said rear anchoring devices for elastically coupling the back of the upper element to the back of the lower element,

55
60
65
70
75

5. In a combination garment, an upper element of a form to encompass the body of the wearer, a lower element of a form to encompass the body of the wearer, oppositely extending spaced front connectors of loop-like triangular contour ex-

tended from the bottom of the front of the upper element, oppositely extending rear connectors of loop-like triangular contour extended from the bottom of the back of the upper element, 5 spaced aligned oppositely extending front anchoring devices secured to and extended from the front of the lower garment and having their outer end terminal portions in the form of couplers having means coacting with said front 10 connectors for slidably and detachably connecting the front of the upper element to the front of the lower element, and spaced aligned oppositely extending rear anchoring devices secured to and extending from the back of the 15 lower element and having their outer terminal portions in the form of couplers having means coacting with said rear connectors for slidably and detachably connecting the back of the upper element to the back of the lower element.

20 4. In a combination garment, upper and lower independent elements for encompassing the wearer and disposed in telescopic relation, said upper element being formed at its front with spaced oppositely disposed front depending elastic 25 extensions of loop-like form and at its back with spaced oppositely disposed rear depending elastic extensions of loop-like form, said lower element being formed at its front with spaced oppositely disposed aligned front anchoring 30 devices extended therefrom and coacting with said front extensions for elastically, slidably and detachably connecting the front of the upper element to the front of the lower element, said lower element being formed at its back with spaced oppositely disposed aligned rear anchoring 35 devices extended therefrom and coacting with said rear extensions for elastically, slidably and detachably connecting the back of the upper element, the said several extensions of loop-like 40 form and the said several anchoring devices further coacting for maintaining said upper and lower elements in telescopic relation, and each of said anchoring devices being formed with an upstanding passage inclining outwardly from its 45 bottom to its top and through which extends a loop-like extension.

5. In a garment a brassière-like body, a resilient member of strap-like form arranged at the lower end of the front of said body, a resilient 50 member of strap-like form arranged at the lower end of the back of said body, each of said members including an intermediate portion and a pair of end terminal portions, said intermediate portions being connected to said body, and each 55 end terminal portion of each of said members being folded to provide a loop, the free terminus of each end terminal portion being secured to said body above the intermediate portions, the remaining part of each end terminal portion being 60 free of connection to said body, said loops being laterally disposed with respect to the ends of the intermediate portions.

6. A combination garment comprising upper and lower body encompassing elements disposed 65 in telescopic relation, spaced connecting devices having their engaging portions horizontally and oppositely extended with respect to each other secured to the lower portion of the front of said upper element, spaced connecting devices having 70 their engaging portions horizontally and oppositely extended with respect to each other secured to the lower portion of the back of said upper element, spaced connecting devices having their engaging portions horizontally and oppositely extended with respect to each other secured 75

to the front of said lower element intermediate the ends of the latter, spaced connecting devices having their engaging portions horizontally and oppositely extended with respect to each other secured to the back of said lower element intermediate the ends of the latter, the connecting devices secured to one of said elements being elastic, and the connecting devices secured to one of said elements having means coacting with the connecting devices secured to the other of 10 said elements whereby said upper element is detachably, slidably and elastically connected to the lower element.

7. In a combination garment, a girdle, a brassière having its lower portion encompassing the upper portion of the girdle, a flat continuous elastic strap having its ends and an intermediate portion secured to the brassière to provide in connection with the latter a pair of spaced oppositely disposed elastic front loops extended from the bottom edge of the front of the brassière, a rear continuous elastic strap having its ends and an intermediate portion secured to the brassière to provide in connection with the latter a pair of spaced oppositely disposed elastic rear loops extended from the bottom edge of the back of the brassière, spaced aligned front anchoring devices carried by the girdle forwardly of the axillary line of the latter and having means coacting with said front loops for elastically, slidably and detachably connecting the front of the brassière to the front of the girdle, and spaced aligned rear anchoring devices carried by the girdle rearwardly of the axillary line of the latter and having means coacting with said rear loops for elastically, slidably and detachably connecting the back of the brassière to the back of the girdle.

8. In a garment, a lower element of a form for encompassing the body of the wearer above and below the hips, a pair of spaced oppositely and horizontally extending front anchoring devices, each being secured at one end to the front of said element forwardly of the axillary line of the latter, said anchoring devices including oppositely disposed couplers at an inclination to the vertical adapted to connect the front of a brassière to the front of said element, and a pair of spaced oppositely and horizontally extending rear anchoring devices, each of said rear anchoring devices being secured at one end to the back of said element forwardly of the axillary line of the latter, said rear anchoring devices including oppositely disposed couplers at an inclination to the vertical adapted to connect the back of a brassière to the back of said element.

9. In a garment, a brassière-like member having the lower edge of its front provided with an elastic element disposed in transverse relation with respect to and having its end terminal portions forming in connection with said front a pair of oppositely and horizontally extending front loops adapted to be connected to the front of a body element of a form to encompass the body of the wearer above and below the hips 60 whereby the front of the brassière will be elastically connected to the front of said body element, said member being provided at the lower edge of its back with an elastic element disposed in transverse relation with respect to and having its end terminal portions forming in connection with said back a pair of oppositely and horizontally extending rear loops adapted to be detachably connected to the back of said body element 65 whereby the back of said member will be elasti- 70 75 75

cally connected to the back of said body element.

10. In a garment, a girdle-like body of a length to extend above and below the hips of the wearer, two pairs of horizontally disposed anchoring devices adapted for detachably connecting a brassière to said body, the engaging portions of the anchoring devices of each pair being oppositely disposed, arranged in spaced relation and extending towards each other from their respective

points of attachment, one pair of anchoring devices being secured at their inner ends to the front of said body forwardly of the axillary line of the latter, and the other pair of anchoring devices being secured at their inner ends to the back of said body rearwardly of the axillary line of the latter. 5

PHILIP H. ROBBINS.
